"DE SCHIE," OF SCHIEDAM, NETHERLANDS, A CORPORATION OF NETHERLANDS.

BOTTLE-BLOWING MACHINERY.

1,148,838.

Specification of Letters Patent. Patented July 27, 1915.

Application filed April 16, 1914. Serial No. 832,341.

To all whom it may concern:

Be it known that I, WILHELM SCHNEEGLUTH, engineer, a subject of the Emperor of Germany, residing at Schiedam, Netherlands, have invented certain new and useful Improvements in Bottle-Blowing Machinery; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

With the usual bottle blowing-machines the bottles assume, together with the molds in which they are contained, at the end of the process an inclined position relative to the vertical, the necks of the bottles pointing upwardly. In this position the head which projects from the upper end of the mold, is caught by a pressure member provided with a layer of asbestos, after which the mold is opened. The pressure member having released the bottle-head, the bottle falls head foremost into a funnel with a cylindrical bottom-part, so that the bottle is guided and arrives with its neck in the corresponding aperture of a periodically rotating table, the bottle-mouth being smoothed in this position by means of Bunsen burners. This device has, however, some drawbacks in blowing bottles, the cross section of which diminishes toward the bottom, as such bottles will not be sufficiently guided in the rectilinear part of the funnel to arrive with their necks exactly above the apertures in the rotary table, while even if the aperture in the table were a larger one and if the bottle, because of its usually short neck, were made to penetrate over a greater distance into the table aperture, its conical end would not be sufficiently supported by the latter.

The object of the present invention is a device which eliminates the above-mentioned drawbacks in order to securely receive the bottle in the aperture of the rotary table and to support it in same so that in this position it may be exposed to the influence of the Bunsen burners.

The principle of the invention is, briefly mentioned, to tip the bottle during its travel from the mold to the rotary table so that it arrives with its bottom downward in the

table aperture. In order to realize this, the bottle falls, after leaving the mold, on an inclined table over the surface of which it glides down, arriving thus on a pivoted part of the receiving table. This pivoted member is depressed by the weight of the bottle, the latter falling consequently into an aperture of the rotary table. If this aperture has so large a diameter that the bottle enters it as far as its widest part, a special guidance of the bottle is superfluous. In case however, the bottle has to remain at a higher level above the table, the table-aperture must be smaller than the cross section of funnel, the insufficiently guided bottle running the risk of being broken by striking against the table. This point is also taken into account in designing the device according to the invention, the bottom part of the funnel being executed with swinging members of such shape that, when closed, they exactly fit around the bottle. When the latter falls down, from the pivoted table into the funnel, its velocity is reduced, the bottle traveling on until it has arrived above the rotary table aperture. The swinging action of the guide members of the funnel can be realized in a very simple manner by keeping them closed by means of balance weights which are light enough to allow the guide funnel of being opened by the bottle arriving with a rather high velocity.

In the accompanying drawing Figure 1 represents a top view, Fig. 2 a side elevation of a device according to the invention in a form of execution applied to machines for blowing the well-known square bottles.

In the form here shown the apparatus comprises an inclined trough-like receiving table *a* onto the upper portion of which the bottles are successively dropped from the mold and on which they successively take a position with the neck end down. The incline of the table is sufficient to cause the bottles to slide downward in the trough thereof, until they reach the tipping table *b*, which, in its normal position, forms a continuation of the bottom of the receiving table and is pivoted at *b*¹ thereto. A stop or head *b*² at the end of the tipping table prevents the bottles overrunning the latter. As soon as a bottle takes up position on the tipping table *b*, the weight of the heavy end of the bottle at the upper end of the tipping table overbalances the counterweight *c* there-

of and swings the table downward. As soon as its downward inclination is sufficient, the bottle, now with its neck end up, discharges into the vertical guide chute *x*, permitting 5 the tipping table to return to normal position under the influence of its counterweight *c*. The bottle drops down the chute *x* attached at its upper end to the receiving table *a*, and passes through the pair of checking 10 jaws *f* pivoted at *g* and *h* respectively. These jaws are shaped to the contour of the bottle but are of somewhat less internal diameter than the small diameter of the bottle. Consequently the speed of the falling 15 bottle is checked, since it must spread the jaws apart against the action of their adjustable counterweights *k* and *l*. Passing through the checking jaws, the bottle is deposited in a suitable registering aperture in 20 the usual rotary receiving table (not shown) and by it conveyed beneath the smoothing burners, with its neck up, instead of down as hitherto.

The apparatus is mounted on any suitable 25 support by means of the brackets *e*, *e*, fast with the funnel-like body piece *d* from which the checking jaws depend and above which the receiving table *a* is supported by strap-like standards *y* and *z*.

Obviously the construction shown may be 30 variously modified to attain the same result without departing from what I claim as my invention.

I claim as my invention:—

35 1. In bottle handling apparatus, a receiving table adapted to receive a bottle from its mold, a pivoted table onto which the bottle is discharged from the receiving table, said pivoted table tipping under the weight 40 of the bottle and discharging the same in inverted position, together with a checking device through which the bottle passes after leaving the tipping table.

2. In bottle handling apparatus, a receiv-

ing table adapted to receive a bottle from its mold, a pivoted table onto which the bottle is discharged from the receiving table, said pivoted table tipping under the weight of the bottle and discharging the same in inverted position, together with a pair of 50 checking jaws between which the bottle is frictionally engaged as it drops from the tipping table.

3. In bottle handling apparatus, a receiving table adapted to receive a bottle from its mold, a pivoted table onto which the bottle is discharged from the receiving table, said pivoted table tipping under the weight of the bottle and discharging the same in inverted position, together with a pair of piv- 55 60 otted counterweighted checking jaws between which the bottle is frictionally engaged as it drops from the tipping table.

4. In bottle handling apparatus, an inclined trough-like receiving table adapted to receive a bottle from its mold, a trough-like pivoted table forming practically a continuation of the lower portion of the receiving table and onto which the bottle passes from the latter, said pivoted table tipping under the weight of the bottle and discharging the latter in inverted position, together with a checking device through which the bottle passes from the tipping table, said 65 70 75 checking device comprising a pair of jaws shaped to the contour of the bottle and yieldably held in frictional engagement therewith to check the speed of its fall.

In testimony that I claim the foregoing 80 as my invention, I have signed my name in presence of subscribing witnesses.

WILHELM SCHNEEGLUTH.
